UNITED STATES PATENT OFFICE.

HARRY I. HANSEN, OF BOONTON, NEW JERSEY.

ROPE-MAKING MACHINE.

SPECIFICATION forming part of Letters Patent No. 604,614, dated May 24, 1898.

Application filed June 9, 1897. Serial No. 640,004. (No model.)

To all whom it may concern:

Be it known that I, HARRY I. HANSEN, of Boonton, in the county of Morris and State of New Jersey, have invented a new and Improved Rope-Making Machine, of which the following is a full, clear, and exact description.

The object of the invention is to provide a machine for making rope which will be of a very simple character and yet will be durable and effective in operation.

Another object of the invention is to provide an improved form of flier and to provide a ready means for removing or for introducing the bobbin in the flier, together with a feed-cone which can be removed and cones of greater or lesser size substituted, and, furthermore, to provide a support for the outer end of the shaft on which the bobbin turns, which support will be capable of expeditious and convenient manipulation.

Another object of the invention is to provide an independent driving mechanism for the flier, the bobbin, and the improved tension device used in connection with the flier and the feed-cone.

It is a further object of the invention to improve upon the traverse of the machine, materially simplifying its construction and insuring reliability of action.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the improved machine, a portion of the casing over the fliers being broken away. Fig. 2 is a vertical section taken on the line 2 2 of Fig. 1. Fig. 3 is a longitudinal vertical section through a portion of a traverse-bar of the flier and one of its heads, illustrating the traverse as in position on the bar and a portion of its casing removed, showing the interior mechanism in side elevation. Fig. 4 is a section substantially on the line 4 4 of Fig. 3. Fig. 5 is an end view of the bearing for the outer

end of the bobbin-shaft. Fig. 6 is a section on the line 6 6 of Fig. 5, and Fig. 7 is a side elevation of the feed-cone and the device employed for supporting the same.

The frame of the machine as shown consists of side pieces A, which are connected at the front by cross-bars 10, 11, 12, 13, and 14. At the bottom portion of the rear end of each side piece a horizontal extension 15 is made, the extensions being connected by cross-bars 16, upon which the bearings for one end of drive-shafts B are secured. The machine illustrated is a double machine, and the mechanism is duplicated above each drive-shaft, each drive-shaft receiving power in an independent manner. Therefore the mechanism belonging to one drive-shaft only will be described.

The drive-shaft B is provided with a fast and a loose pulley, (designated as 17 and 18,) and near these pulleys a cone-pulley 19 is secured upon the drive-shaft, while near the opposite end of said shaft a plain pulley 20 is secured, and a second cone-pulley 21, which is of less diameter than the cone-pulley 19, as shown in Fig. 2. The forward end of the shaft is mounted to turn in a box 22, located upon a cross-bar 23.

At the forward end of the machine, upon the upper cross-bar 14, two posts 24 and 25 are upwardly projected, the post 24 being provided with a horizontal extension 26 and with an opening 27 near its lower end, having a lug 28 near each side. A lever 29 is fulcrumed in the lugs 28, as shown particularly in Fig. 7, the said lever being carried through said opening 27 into the space between the two posts 24 and 25, being provided upon its upper face with a segmental shoe 30.

Ears 31 are formed upon the upper portion of the post 25, at each side of an opening therein, and a second lever 32 is fulcrumed in the ears 31, the upper lever 32 being also carried into the space between the two posts 24 and 25, terminating in a segmental shoe 33, which faces the shoe 30. The two shoes are adapted to hold between them a feed-cone C. This cone is made in two sections 34 and 35, being provided at its larger end 100

with a flange 36, as is also shown in Fig. 7. A spring 37 holds the lever 29 normally in clamping engagement with the feed-cone, while a second spring 38 performs the same 5 function for the opposing lever 32.

On the cross-bar 10, at the upper rear portion of the machine, a bearing 39 is secured, open at the front and at the rear. This bearing or box is provided with lugs 40, between which 10 one end of a lever 41 is secured, being weighted at its free end, and a thrust-plate 42 is carried by the lever 41, serving to close the outer end portion of the opening in the said box 39. By moving the lever 41 to the position 15 shown in dotted lines in Fig. 5 the shaft that is journaled in the box 39 may be drawn out therefrom; but while the thrust-plate is in its lower position the shaft will be prevented from leaving the box as effectively as 20 though the outer side of the box were closed.

A box 43 is located on the cross-bar 13, a second box 44 is secured upon the cross-bar 12, while a third box 45 is placed upon the cross-bar 11 near the rear end of the machine-frame. The flier D is best shown in Fig. 2, and consists of two heads *d*, connected by two traverse-bars 46 and 47, placed diametrically opposite. Each head consists of a plate 49, having an inwardly-extending flange 50, the flanges of the two heads facing one another, each flange 50 having an annular member or subflange 48 upon its inner face near its inner end. The flange 50 of the right-hand head is wider than the corresponding flange of the left-hand head, and the right-hand head is provided with an inner plate 51, secured to the auxiliary flange 48.

In the inner face of each traverse-bar 46 and 47 a longitudinal slot 52 is formed, while 40 in the outer or opposing face of each traverse-bar a wider slot 53 is produced. The said slot 53 is divided longitudinally for a portion of its length by a central partition 54, and the ends of the wider slot 53 are curved, as 45 shown in Fig. 1, the central partition 54 stopping short of said ends. Along the margin of the wider slot 53 pins 55 are arranged, as shown in Figs. 1, 3, and 4. A traverse E is held to slide upon each of the bars 46 and 47, 50 but only one of said traverses is brought into action at one time. Each traverse, as shown in Figs. 3 and 4, consists of a casing 56, which is usually made in two sections centrally divided and connected by bolts or their equivalents.

In the bottom of the casing of each traverse 55 a circular opening 57 is made, which neatly yet loosely fits around the traverse-bar. Within the left-hand portion of the casing a chamber 58 is formed, while near the right-hand portion of the casing a corresponding yet shorter chamber 58^a is made. The larger chamber 58 is connected with the circular bottom opening 57 through the medium of a channel 59, and a slot 60 is horizontally made 60 in the left-hand portion of the traverse, as

shown in Fig. 3, and at the central bottom portion of the slot a depression or a recess 61 is produced.

A pulley 62 is secured upon a shaft 63 below a gear-wheel 65, made upon the enlarged portion of the shaft and held to turn in the chamber 58^a, the lower end of the shaft 63 being provided with ball-bearings 64, contained within the recess 61. Ball-bearings 66 are likewise provided for the upper end of the shaft 63, being adjustably held in position by an adjusting-screw 67 at the top portion of the traverse. A shaft 72 is located within the channel 59, connected with the chamber 58, the shaft 72 being of much less diameter than the diameter of the channel, as shown in Fig. 4. Within the chamber 58 the shaft 72 is enlarged, and its enlarged portion is formed with a gear-wheel 68 and a plain surface 68^a 80 below the same. The shaft 72, however, is capable of lateral movement in the chamber 58. The upper end of the shaft 72 is provided with ball-bearings 69, held in position and controlled by an adjusting-screw 70, while 85 roller or ball bearings 71 are placed in the bottom portion of the chamber 58, upon which the lower end of the enlarged section 68^a of the said shaft 72 has bearing.

A spur-wheel 73 is secured upon the lower 90 end of the shaft 72, and the said wheel is provided with an extension 73^a at its bottom, which is in the form of a stud. This stud is adapted to engage with one side or the other of the partition 54 in the outer slot 53 of a 100 traverse-bar, the teeth of the wheel being arranged for engagement with the pins 55, located in the said slot. The two gear-wheels 65 and 68 are connected by a pinion 69^a, (shown in Fig. 3,) and when the rope is passed 105 around the pulley 62 to an engagement with the bobbin and the machine is in motion the rotation of the pulley 62, caused by the friction of the rope, will revolve the shaft on which the pulley is secured, and the gearing 110 just described will transmit power to the shaft 72, causing the wheel 73 to revolve and the traverse to move up and down the traverse-bar upon which it is placed first at one side of the partition 54 on said bar and then at the 115 opposite side, causing the rope to be evenly wound upon the bobbin, to be hereinafter described. A wheel 75 is journaled in the bottom portion of each traverse and enters the smaller groove 52 in the bottom of the traverse-bar, being a guide for the traverse on 120 said bar.

At the right-hand end of the flier D a tubular shaft 76 is secured or integrally formed, being journaled in the boxes 43 and 44. This 125 shaft has a pulley 77 attached to it, connected by a belt 78 with the plain pulley 20 on the drive-shaft B, as shown in Fig. 2. A tubular shaft 79 is loosely carried through the left-hand head of the flier, being journaled in the 130 box 45 near the left-hand end of the machine, and at the outer and left-hand end of the sec-

ond tubular shaft 79 a cone-pulley 80 is secured, connected by a belt 81 with the lower cone-pulley 19, thereby providing for an increase or decrease of speed for the said rear 5 tubular shaft.

At the inner end of the tubular shaft 79 a disk 82 is formed, and the supporting-shaft 83 for the bobbin 84 is passed through the bobbin and through the tubular shaft 79, having its right-hand end detachably journaled in the plate 51 of the right-hand end of the flier, while the left-hand end of the said flier-shaft is made to enter the extreme left-hand box 39 and is held in place by the thrust-plate 42 for said box. One head of the bobbin is detachably secured in any suitable or approved manner to the disk 82 on the tubular shaft 79. Within the right-hand head of the flier, adjacent to the traverse-bar 47, a set of tension-pulleys 85 is secured upon a shaft which extends from the outer end of said head to its inner plate 51, while a second and corresponding series 86 of these tension-pulleys is similarly placed opposite in 25 the right-hand head of the flier adjacent to the opposing traverse-bar 46, as shown in Fig. 2.

A tubular shaft 87 is held to turn in the tubular shaft 76 belonging to the flier. This inner tubular shaft 87 may be termed a 30 "feed" or a "guide" shaft and extends within the right-hand head of the flier. The feed or guide shaft 87 is provided at its right-hand end with an attached conical pulley 88, connected by a belt 89 with the lower conical pulley 21, so that the speed of this guide or feed shaft may be increased or decreased, as desired, but the speed at which the flier is turned is preferably uniform.

At that end of the feed or guide shaft 87 40 which enters the head of the flier a gear 90 is secured, which meshes with a pinion 91, mounted to drive the series of tension-pulleys 86, also meshing with a second pinion 92, mounted to drive the opposing set of tension-pulleys 85.

The fiber 93, from which the rope is to be made, is passed through the feed-cone, from which it will meet with more or less resistance, and is carried through the feed or guide 50 shaft 87 and around the various tension-pulleys 85 and 86, as shown in Fig. 2, out from the head over a whirl 94, a second whirl 95 being placed between the tension-pulleys 85 and 86. After the fiber has passed from the 55 outer whirl 94 it is carried around the pulley 62 in a traverse and is attached to the bobbin 84.

It will be observed that the guide or feed 60 shaft, the bobbin-shaft, and the flier-shaft are all independently driven. Consequently when the fiber is led and secured, as above mentioned, and the machine is set in motion a twisting action will take place between the right-hand end of the flier and the feed-cone, 65 said twisting action continuing in a measure within the right-hand head, but at this point

the twisted strands are designed to be set and placed under such tension as will produce a perfect rope, the traverse simply serving to direct the winding of the rope thus made on 70 the bobbin.

A casing 96 is made to cover the upper portion of each flier on the machine, and each casing is provided with a door 96 to admit of the removal of the bobbins, and a second 75 casing 97 is provided for the lower portion of each flier, as shown best in Fig. 2.

It is sometimes very desirable that the flier should be stopped almost instantly after the belt has been shifted from its driving-pulley. 80 To that end I provide a brake-lever 98, which is fulcrumed on a bracket 99, and one of these levers is used in connection with each flier. An arm 100 is pivoted to the lower end of each brake-lever 98, the arm being held to 85 slide through the end wall of the casing 95 for the flier, being provided at its inner end with a shoe 101, adapted to engage with the head-section *d* of the flier, as shown in Fig. 1. A spring 102 is coiled around the arm 100, 90 having bearing against the casing 95 and being connected with the arm 100, around which it is coiled. The spring normally holds the shoe 101 from engagement with the flier, the lever at that time being in the position shown 95 in positive lines in Fig. 2; but when the motion of the flier is to be stopped the lever is to be carried outward, as shown in dotted lines in Fig. 2, which will bring the shoe 101, connected with the said arm, in frictional engagement with the head of the flier.

Having thus described my invention, I claim as new and desire to secure by Letters Patent—

1. In a rope-making or similar machine, the 105 combination, with a flier, a bar whereof is provided with a longitudinal slot in one face and a wider longitudinal slot in its opposite face, together with a longitudinal rib extending along the wider slot and stopping 110 short of its ends, the walls of the wider slot being provided with teeth, of a traverse mounted to travel on the bar of the flier, having a guide-wheel arranged to enter the annular slot in said bar, a driving-wheel held 115 in engagement with the toothed wall of the wider slot, a pulley over which the yarn or rope is to be carried, and a driving connection between said pulley and the driving-wheel of the traverse. 120

2. The combination, with the bar of a flier having a longitudinal slot in one face and a wider slot in the opposite face, a rib dividing the wider slot for a portion of its length, the walls of the wider slot having teeth or projections, of a traverse held to travel on said bar, provided with a guide-wheel which enters the narrower slot, the said traverse being provided with a shaft having lateral movement, a driving-wheel carried by the shaft 130 and arranged for engagement with the projections from the wall of the wider slot, a

pulley adapted for engagement with the yarn or rope passed to the traverse, and means for driving said shaft from said pulley.

3. In rope-making machines or machines of like type, a flier provided with a guide-bar, in combination with a traverse consisting of a casing having an opening to receive the bar of a flier, a shaft above the opening, extending within the same and mounted to have rotary and lateral movement, a driving-wheel

carried by the lower end of said shaft, a pulley adapted for frictional engagement with the rope or yarn, and a driving connection between said shaft and said pulley.

HARRY I. HANSEN.
